(57) **CLAIM**

The ornamental design for an air filter assembly as shown and described.

DESCRIPTION

FIG. 1 is a top, front, right perspective view of the air filter assembly;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a bottom, front, right perspective view thereof;

FIG. 9 is a top, front, right exploded view thereof;

FIG. 10 is a bottom, front, right exploded view thereof;

FIG. 11 is a top, front, right perspective view of the air filter assembly;

FIG. 12 is a front elevational view thereof;

FIG. 13 is a rear elevational view thereof;

FIG. 14 is a left-side elevational view thereof;

FIG. 15 is a right-side elevational view thereof;

FIG. 16 is a top plan view thereof;

FIG. 17 is a bottom plan view thereof;

FIG. 18 is a bottom, front, right perspective view thereof;

FIG. 19 is a top, front, right exploded view thereof; and,

FIG. 20 is a bottom, front, right exploded view thereof.

The evenly spaced broken lines depict portions of the air filter assembly that form no part of the claimed design. The dot-dash chain lines depict a boundary of the claimed subject matter and form no part of the claimed design. The appearance of any portion of the air filter assembly between the jagged break lines, regardless of length, forms no part of the claimed design.
